UNITED STATES PATENT OFFICE.

JOHN KIRKALDY, OF LONDON, ENGLAND.

PORTABLE DISTILLING APPARATUS.

SPECIFICATION forming part of Letters Patent No. 718,209, dated January 13, 1903.

Application filed April 18, 1901. Serial No. 56,425. (No model.)

To all whom it may concern:

Be it known that I, JOHN KIRKALDY, a subject of the King of England, residing at London, England, have invented certain new and useful Improvements in or Relating to Portable Distilling Apparatus, (for which application for Letters Patent has been made in Great Britain, under No. 5,219, dated March 12, 1901,) of which the following is a specification.

This invention relates to portable distilling apparatus, and is particularly applicable to army requirements. The apparatus, besides distilling its appropriate quantity of "gained"

water from impure, muddy, or salt water, can also produce a much larger quantity of mixed boiler-steam and gained water if the water which has to be distilled is pure enough for feeding the boiler without previous treatment.

The apparatus comprises a suitable framework mounted, preferably, upon four wheels and carrying at one end the boiler, of a light quick-steaming vertical type, and at the other end the seat for the driver, besides any tanks or receptacles which may be placed underneath the seat.

The frame comprises two horizontal longitudinal members connected at each end in any suitable manner, as by cross members secured to the longitudinal members or by other portions of the apparatus.

The boiler lies between the two horizontal members at or near one end; and between the members and more or less in the central line of the vehicle lies the evaporator, preferably of a vertical type and depending below the framing, whereby the center of gravity is kept low and a convenient rise to the condenser is obtained without the latter being elevated unduly.

The pump which circulates the cooling-water for the condenser is placed between the frames a little in advance of the evaporator and at one side of the center line, the condensing apparatus being by preference still farther forward between the frames and at the opposite side. By this disposition the vehicle is well balanced throughout. In addition to circulating the water for the condenser the pump may also serve to feed the boiler.

The driver's seat and footboard, &c., are at

the front end of the frame and over the fore-carriage. The chimney for the boiler is hinged and adapted to fold down forward in the center line of the vehicle, lying when down over the top of the evaporator and between the circulating-pump and the condenser. 55

The boiler may be provided with an extra feed-pump injector, &c., and the usual safety-valves and fittings, while the necessary pipes, valves, gages, and other connections are provided for the other portions of the apparatus, so that the latter may be employed in any or all of the various functions they are fitted to 65 fulfil.

This apparatus combines for the first time, it is believed, in a single vehicle the whole of the plant requisite for supplying not merely distilled potable water from impure sources, 70 but hot water for various purposes, while the engine can be used for driving purposes, as well as for pumping, and the pump itself may be used for distributing water which may not have been treated in the apparatus at all— 75 as, for example, for extinguishing fires or for irrigation or sanitary purposes. With this apparatus at hand hot water for all camp purposes is immediately obtainable, whether for drinking, for baths, or for medical purposes, &c.

Though I do not wish to confine myself to precise details of construction of the various parts, the following are what I prefer to use. 85 The boiler may be of any type of light compact form, preferably vertical, and capable of raising steam very quickly when the fire is applied. I prefer to make it with a large fire-box to burn any fuel that may be at hand; but it can be fired with liquid fuel, if desired. 90 The evaporator would comprise a vertically-disposed cylindrical vessel with a large flanged door in the lower portion, to the lid of which are secured a number of coils or a single coil through which steam is driven for 95 the purpose of heating the water in the evaporator. The coil is entirely supported by the door or cover, so that it may be easily removed and another one substituted, if necessary, without disturbing the rest of the apparatus. The fresh-water condenser comprises one or more vertical tubes, inside which are arranged one or more coils of piping, preferably larger at their upper ends and dimin-

ishing toward their lower ends. The cooling-water enters at the bottom and rises upward through the large tube or casing, while the steam from the evaporator enters the coils at the top and escapes as water at the bottom into a lower chamber, which forms a stand or base upon which the condensing apparatus is secured. The fresh water is drawn from the upper portion of this base, which may be provided with mud-holes, draw-off cocks, &c.

The vehicle is supplied with platforms or extensions as required, upon which men can sit, so that the apparatus can carry its full complement of hands for any purpose.

15 The feed-heater and exhaust-condenser may be placed in any convenient position; but, perhaps, the most suitable is between the boiler and the evaporator. The precise form of the feed-heater may be varied; but I prefer to adopt a horizontal type, which can be carried upon a cross-framing or may be secured to the boiler or to the evaporator.

In the accompanying drawings, Figure 1 is a plan of one construction of portable distilling apparatus according to this invention. Fig. 2 is a side elevation of the same, a portion being removed for the sake of clearness. Figs. 3, 4, and 5 are vertical sections of the evaporator, the main condenser, and feed-water heater and exhaust-condenser, respectively, and are drawn to a larger scale than Figs. 1 and 2. Fig. 6 is a sectional view showing in detail the float-operating valves for maintaining an approximately constant water-level in the evaporator. Fig. 7 is a vertical section of the main condenser at right angles to the section shown in Fig. 4.

With reference first to Figs. 1 and 2, A is a frame or support having two main longitudinal members and a fore-carriage A'. The frame is cross-braced in any convenient way, as at A², and supported through springs A³ upon wheels A⁴, a driver's seat A⁵ and foot-board A⁶ being placed at the front and platforms or extensions A⁷ at the rear. The frame and its adjuncts are hereinafter described as the "truck."

At the rear of the truck and between the longitudinal members a steam-generator B is mounted, and in front of this steam-generator, also between the longitudinal members of the truck, but a little to one side of the central line, and placed as low as possible is an evaporator C. In front of the evaporator and on the other side of the central line of the truck is a small vertical engine D, while upon the opposite side of the truck immediately behind the driver's seat A⁵ is a condenser E.

10 A feed-water tank F is placed upon the truck immediately in front of the steam-generator B, and on top of the feed-tank is a feed-water heater and exhaust-condenser G. All these main elements of the apparatus are made as light as possible and are arranged so that the weight is as nearly as may be equally distributed over the truck.

The arrangement of the various pieces of apparatus in operative condition upon the one truck in such a way that the whole plant is balanced and easy of transport is an essential feature of this invention.

In the accompanying drawings the course of the steam from the generator is indicated by plain arrows, the course of the condensed water returning to the generator is indicated by plain dotted arrows, the course of the fresh water for condensing purposes and for supplying the evaporator is indicated by double-headed arrows, and the course of the steam from the evaporator to the storage-tank is indicated by triple-headed arrows.

15 Steam from the generator B passes through a stop-valve B' to a pipe H, whence it proceeds through a pipe H' to coils C' in the evaporator C. These coils are not shown in Figs. 1 and 2, but may be seen in Fig. 3. On leaving the coils C' the steam, which by this time is partially or wholly condensed, passes by a pipe H² to a chamber E⁷ in the top of the condenser E, with which chamber communicates a coil E', Fig. 4, of the condenser E. The lower end of this coil E' makes connection at E² with pipes H³ and H⁴, so that the water descending the coil E' may pass either through the pipe H³ to a fresh-water storage-tank J or be returned through the pipe H⁴ to the feed-water tank F. The steam from the generator B after passing through the pipe H also proceeds by a pipe H⁵ to the engine D and causes that engine to operate a pump D', which is provided with a suction-inlet D² and delivers water from that inlet through a pipe D³ to the casing of the condenser E. The water after passing through the casing makes its exit at D⁴, the outlet at that point being provided with a hose-fitting, so that the water pumped may be directed to any suitable spot and used, for instance, for extinguishing fires or for sanitary purposes in camp. The suction-inlet D² is also provided with a hose-fitting.

45 A valve-controlled pipe D⁵ leads from the outlet D⁴ to the evaporator C, the inlet to the latter being controlled by a valve C². An outlet-valve C³ for the evaporator is also provided, and these valves C² and C³ are conveniently controlled by a lever C⁴, (shown in Fig. 6,) actuated by a float C⁵ in the evaporator. When the float sinks, the inlet-valve is opened and the discharge-valve closed, and vice versa, so that the level of water in the evaporator is kept approximately constant.

50 A pipe H⁶ leads from the stop-valve B' of the steam-generator B to a boiler-feed pump K, mounted upon the steam-generator. This pump has a suction-pipe K', communicating with the feed-water tank F, and a delivery-pipe K², leading to the space within the feed-water heater G, exterior to the coil G', Fig. 5. At the other end of the feed-water heater is a pipe K³, leading to the interior of the steam-generator B. The exhaust from the engine D comes through a pipe D⁶ to one end of the coil G' within the feed-water heater G and is

joined by the exhaust from the boiler-feed pump K, which is conducted to the end of the coil G' by a pipe K⁴. The exhaust-steam from the engine and pump is condensed in its passage through the coil G' and may pass out through a pipe K⁵ to the feed-water tank F. A valve-controlled outlet-pipe K⁶ is, however, provided, so that the hot water may be drawn off for washing or other purposes.

10 The steam raised in the evaporator C passes out through a valve-controlled pipe C⁶ to a chamber E⁸ in the top of the condenser, with which chamber communicate two coils E⁸ E¹⁰, Fig. 4, in the condenser E. These coils communicate with the fresh-water-storage tank J, into which the pure distilled water flows and may be withdrawn through the cock J'.

15 A pipe D⁷ connects the discharge-outlet for the circulating water of the condenser with the pipe H⁴, leading to the feed-water tank F, and forms a supplementary feed-inlet. At the bottom of the evaporator C is a cock C⁷, which communicates with the bottom portion of the coils C', so that hot fresh water may be drawn therefrom. A mud-door C⁸ and a brine-valve C⁹ are also fitted to the evaporator. The steam-generator B is provided with a hinged chimney B², which can be made to assume an approximately horizontal position, its upper 25 end being accommodated in a support B³ at the back of the driver's seat A⁵.

20 As may be seen by reference to Fig. 3, the steam-heating coils C' of the evaporator C are fitted to the inside of a flanged door C¹⁰, which 30 is hinged, as at C¹¹, so that by opening the door the coils may be readily inspected and, if necessary, replaced. In Fig. 3 the door C¹⁰ is shown open, exposing the coils C', the closed position being indicated in chain-lines. C¹², 35 Fig. 3, are baffles to throw back any water and prevent it being carried over by priming.

30 The apparatus may be provided with the usual fittings—such as steam-gages, safety-valves, water-gages, &c. Some of these fittings are illustrated in the drawings, but are 45 not particularly described, as they present no special features.

40 The following is a convenient method of working the apparatus above described: After raising steam to working pressure in the steam-generator B it is admitted to the feed-pump K by opening the valve controlling the pipe H⁶. The engine D is then started to work the circulating-pump D', and steam is admitted to the evaporator C, which has been 50 previously filled to the working level with water. The stop-valve controlling the pipe C⁶ is then opened and the valve controlling the pipe D⁵ regulated so that the water in the 55 evaporator is kept at its proper level. If necessary, the brine-valve C⁹ is opened to keep down the density, which preferably should

not exceed six one-hundredths by the salinometer. The valve controlling the pipe H², leading from the evaporator-coil C' to the condenser E, is regulated to keep a suitable pressure in the evaporator, the outlet at E² from the coil E' being opened either to the tank J or through the pipe H⁴ to the feed-tank F, as may be desirable.

70 In addition to the other points mentioned it may be noted that the water issuing from the circulating-outlet D⁴ is usually warm and can be used for baths, washing, or stable purposes. The temperature of this water may 75 be varied by altering the speed at which the circulating-pump D' works.

75 The various connected passage-ways through which steam and water circulate, consisting principally of pipe-sections, will 80 for convenience be referred to in the claims as "conduits."

What I claim as my invention, and desire to secure by Letters Patent, is—

1. In a portable distilling apparatus, the 85 combination of a steam-generator, an evaporator, a condenser, a conduit leading from the generator through the evaporator and condenser successively, a separate conduit leading from the interior of the evaporator through 90 the condenser, means for circulating a cooling medium around the conduits in the condenser, and conduits arranged to convey condensed water from the condenser to the generator.

95 2. In a portable distilling apparatus, the combination of a steam-generator, an evaporator, and a condenser, a conduit leading from the generator through the evaporator and condenser successively, a separate conduit 100 leading from the interior of the evaporator through the condenser, a conduit arranged to convey condensed water from the condenser to the generator, means for circulating a cooling medium around the conduits in the condenser, and means for automatically regulating the quantity of water in the evaporator.

105 3. In a portable distilling apparatus, the combination of a steam-generator, an evaporator, a condenser, suitable conduits leading 110 from the generator through the evaporator and condenser successively and thence back to the generator, a separate conduit leading from the interior of the evaporator through the condenser, and a tank arranged to receive the condensed water from said latter conduit.

115 In testimony whereof I have signed my name to this specification in the presence of two subscribing witnesses.

JOHN KIRKALDY.
